PROPELLER HAVING AN AUTOMATICALLY VARIABLE PITCH

Dimitri Sensaud de Lavaud, Paris, France

Application January 31, 1939, Serial No. 253,719
In France November 8, 1938

5 Claims. (Cl. 170—164)

This invention relates to propellers, and more particularly to propellers having blades the pitch of which is automatically variable during use.

One of the objects of the present invention is to provide novel means for governing torques which act upon the blades of a propeller having an automatically variable pitch.

Another object of the invention is to provide an automatically variable pitch propeller which is simple in construction and highly efficient.

A further object is to provide novel means for controlling automatically the pitch of the blades of a propeller, which means can be easily adjusted in accordance with the structural peculiarities of the vehicle and propeller with which it is employed.

The above and further objects and novel features will more fully appear from the detailed description when the same is read in connection with the accompanying drawings. It is to be expressly understood, however, that the drawings are for purposes of illustration only and are not intended as a definition of the limits of the invention, reference for this latter purpose being had to the appended claims.

In the drawings, wherein like reference characters refer to like parts throughout the several views,

Fig. 1 is a front view, partly in section and partly diagrammatic, of a propeller blade and mounting therefor which is employed with the present invention;

Fig. 2 is a view which is primarily sectional with parts broken away and with parts in elevation of one embodiment of the invention wherein the blade hub has shifted angularly through a small distance;

Fig. 3 is a vector representation of certain forces acting upon a propeller as produced by the means shown in Fig. 2;

Fig. 4 is a front view in elevation of a variable pitch propeller embodying the present invention; and

Fig. 5 is a side view in elevation of said propeller.

The form of the invention illustrated in the accompanying drawings, by way of example, comprises means for aiding in the automatic adjustment of the pitch of the blades of a propeller such as an aeroplane propeller. The latter is provided, for example, with two blades, each of which is angularly movable about an axis which is angularly disposed relative to the axis of the blade, the axis of pivotal movement being in spaced relation to the axis of rotation of the propeller. When the axis of angular movement and of rotation are projected upon a plane parallel to them both, the projections are not necessarily perpendicular to one another but are preferably mutually inclined at an angle slightly less than 90°. The novel

adjusting member employed with this propeller is constituted by resilient adjustable means which exert a radial thrust upon each of the blades when the latter are at rest, and which exert a tangential, or approximately tangential, thrust upon each of said blades when the latter have angularly shifted from the rest position, thus producing a torque which tends to increase the angle through which the blade has moved.

- 10 In the diagrammatic form shown in Fig. 1, a propeller blade mounting is illustrated, which is similar to that shown in my Patent No. 1,943,210, and which comprises a pair of blades 1, each of which are rigidly secured by means of a socket member 2 to a torsion or pivot rod 3, the axis of which is angularly disposed relative to that of the blade. Rod 3 is fixed at the inner end thereof to a suitable sleeve member (not shown) in any suitable manner, such as that illustrated in the above mentioned Patent No. 1,943,210. The opposite or outer end of rod 3, to which is attached blade 1, can pivot or move angularly about the longitudinal axis of the rod, when a torque is applied thereto. The sleeve member is rigidly attached to and preferably integral with a hub (not shown). The latter is keyed in a conventional manner to a driving shaft having an axis O perpendicular to the plane of the figure. The axis of rod 3 is at a distance a from that of the driving shaft. In a plane containing the axis of one of the rods 3 and parallel to the axis O, the axis of rod 3 is preferably inclined relative to a projection of axis O upon said plane at an angle differing slightly from 90°, or at right angles to said projection.

- If one of the blades were moved about the axis of its torsion rod 3 through an angle of 360°, the neutral longitudinal axis of the blade would describe a cone of revolution and a point on said axis would describe a circle, e. g., circle 1a (Fig. 1). When the blades are rotating about the axis of rotation O of the driving shaft, certain forces mentioned below act upon each blade causing a pivotal or angular movement thereof about the axis of the respective torsion rod, thereby varying the pitch of the blade under certain operating conditions.

During rotation of the propeller, each blade is subjected to the following torques:

- 50 1. An aerodynamic torque which tends to reduce the pitch;
2. A centrifugal torque which tends to increase the pitch;
55 3. A return torque produced by the torsion of the rod;
4. A torque or natural torsion tending to hold the blades at a minimum pitch; and
60 5. Devices which are responsive to the thrust of the blade on the hub are provided for assisting

the pivoting of the blade after the pivoting has commenced, the devices therefore producing a fifth torque which acts upon the blade.

It has been found difficult to obtain thus a perfect pitch control because, in addition to the fact that no two propellers can be made exactly alike, the aerodynamic features of the particular aircraft upon which the propeller is mounted have an effect upon the operation of the propeller. Consequently, novel means are provided for producing an additional torque, which means can be adjusted to compensate for the individual characteristics of the particular propeller and of the particular craft upon which the propeller is mounted.

In the embodiment shown in Fig. 2, the root or base 2 of blade 1 is shown in a position occupied after having rotated through a small angle from a rest position.

The root 2 of the blade, because of the strains acting thereon, exerts a lateral thrust upon a hub 20 (Fig. 2) by means of lugs 6, 6', having, for example, rounded heads 7, 7', the latter being in contact with bearings 8, 8' which are rotatably mounted upon the hub. In equilibrium position the points of contact between heads 7, 7' and bearings 8, 8' are on lines joining the centers of bears 8, 8' with the center of root 2. As a result, the reactions exerted by bearings 8, 8' on lugs 6, 6' are directed through the center of said root and apply no turning torque thereto. However, as soon as the blade has rotated slightly around the axis of rod 3, turning root 2 slightly, for example, in a clockwise direction, as viewed in Fig. 2, the axes of lugs 6, 6' no longer pass through the contact points of heads 7, 7' and bearings 8, 8', and said axes no longer coincide with the lines joining the centers of bearings 8, 8' and the center of root 2. As a result, any lateral force applied to root 2 in the direction of bearings 8, 8' produces reactions from bearings 8, 8' which are directed eccentrically relative to the root center, thereby producing clockwise torques, the latter tending to further displace the root 2 in a clockwise direction. Therefore, the thrust on the root or base 2 tends to increase the angle through which the blade has moved, and thus produces the above-mentioned fifth torque.

Novel means are provided for producing an additional correcting torque comprising two adjacent cylinders 9, 9', the axes of which extend radially of the base 2. In each of the cylinders is a piston 12 which is urged toward the base 2, i. e., toward the inner extremity of the cylinder by suitable resilient means such as spring washers 13. The thrust of the washers is communicated to the base 2 by means of a driving rod or intermediate member 14 which engages the base 2 and the piston 12, for example, in ball and socket joints 15 and 16 respectively.

When the propeller is at rest, it is in such a predetermined position that the rod 14 is normal to the base 2, that is, the axis of the rod extends radially of the base. However, when the blade angularly shifts from the initial position, the driving rod 14 takes an oblique position relative to the root and transmits thereto the thrust of washers 13. This thrust produces a torque which acts on the root, as will be explained with reference to Fig. 3.

In Fig. 3, assume AB to represent the axis of rod 14, and T to represent the thrust acting normally to the base 2. When the latter angularly shifts a slight amount the rod 14 will assume a direction

PQ at an angle a to AB. The thrust of washers 13 now becomes

$$T' = \frac{T}{\cos a}$$

5 If T' acts at the point Q it produces a tangential thrust t thereupon which can be expressed:

$$t = T' \cos b$$

10 This thrust produces the correcting torque.

Transposing t into terms of T , a and a it is found, considering o to be the center of base 2, that $b = 90 - (a + c)$, therefore

$$15 t = \frac{T}{\cos a} \sin (a + c)$$

Since the radius OB of the base is much greater than the length AB of the connecting rod, it is seen that angle a is also much greater than angle c and thus

$$\frac{\sin (a - c)}{\cos a}$$

is approximately equal to

$$25 \frac{\sin a}{\cos a}$$

or $\tan a$; therefore said quantity increases when the blade rotates. Consequently, the correcting torque would increase if T remained constant.

30 But thrust T being produced by the washers decreases as the spring expands. The tangential thrust t is thus the product of two quantities T and $\tan a$ (approx.), one of which decreases while the other increases when the base angularly

35 moves from the initial position. The torque correcting means can be so designed whereby the thrust t varies in a predetermined manner, thus producing at all times a desired correcting effect.

Suitable means for varying the compression of 40 the resilient means 13 are provided comprising a threaded cap 16 upon each of the cylinders. By angularly moving the cap the position thereof axially relative to the cylinder can be varied and thus the compression of the spring can be adjusted.

When the blade root 2 is in inoperative position, i. e., when said blade is in equilibrium position and has not been laterally or angularly displaced, the axes of driving rods 14, 14' are coincident with

50 the axis of blade 2. As a result, the forces exerted upon said rods by resilient washers 13 are directed through the axis of root 2 and produce no turning torque on said root. Similarly, the reaction of bearings 8, 8' to lateral thrust exerted

55 on said root in the direction of said bearings by lugs 6, 6' is directed through the axis of said root, also producing no turning torque. However, during rotation of the propeller, the blade root 2 is given an angular displacement, for example, in a clockwise direction, as viewed in Fig. 2, and is

60 also subjected to a lateral thrust in an upward direction, as viewed in said figure. As a result of the angular displacement of the blade, the axes of driving rods 14 are displaced relative to

65 the center of root 2 and apply a clockwise turning torque to said root. Similarly, the equilibrium position of lugs 6, 6' is disturbed so that the lateral thrust on root 2 produces eccentric reactions from bearings 8, 8', said reactions also

70 applying a clockwise torque to the root 2. Thus, the provision of applicant's novel lug and bearing arrangement produces one additional torque, and the provision of the novel resilient washer and rod structure produces another additional torque when the blade is in operation and has been dis-

placed by the aerodynamic and centrifugal forces. However, neither of these torques acts on the blade root when the blade is inoperative and in equilibrium position.

There is thus provided novel means for controlling the balance of forces tending to shift the blades of a propeller. The means are simple and rugged in construction and are easily adjusted.

Although only one embodiment of the present invention has been illustrated and described in detail, it is to be expressly understood that the same is not limited thereto. For example, instead of employing spring washers 13 it is possible to use a suitable coil spring or a plurality of superposed coil springs. Further, instead of having two torque correcting devices 9, 9' any desired number can be used. Various changes in the design and arrangement of the parts can be made without departing from the spirit and scope of the invention as the same will now be understood by those skilled in the art. For a definition of the limits of the invention, reference will be had primarily to the appended claims.

What is claimed is:

1. In a variable pitch propeller, a plurality of blades, a torsion rod for each blade, a hub including means for mounting each torsion rod, the axes of said rods being in spaced relation and oblique relative to the axis of rotation of the hub, means for exerting a torque upon each of said blades, each of the last named means being operable after the blade to which it is operatively connected has angularly moved about the axis of its respective torsion rod from a predetermined position, said torque being in response to a lateral displacement of each blade upon the hub, one or more intermediate members for each one of said blades, and resilient means for urging each intermediate member towards the blade to which it is operatively connected, said intermediate members extending radially to the cross section of their respective blade when the latter is in an initial position and extending obliquely to a radius of said cross section when the respective blade has moved angularly from said initial position.

2. In apparatus of the class described, a plurality of pivot rods, a blade secured to each rod, the axes of each of said rods being inclined relative to the axis of the blade secured thereto, a driving shaft, a hub operatively connected to said shaft, means upon said hub for mounting each of said rods, the axis of said shaft and rods being non-intersecting, means responsive to a lateral displacement of each blade upon the hub for assisting a pivotal movement of the blades after said movement has begun from a predetermined position of the blades, means for exerting a resilient torque upon each of said blades, and means for adjusting the last named means, said resilient torque acting upon each blade being variable in a predetermined manner in response to the angular movement of the blade from a predetermined position.

3. A variable pitch propeller comprising blades supported so as to be pivoted about the longitudinal axes thereof and to be laterally displaced from a predetermined equilibrium position by the forces set up when said propeller is rotated in a fluid medium, torsion rods for supporting said blades and for resisting the pivotal movement thereof from said equilibrium position, control means connected to each of said blades, each of

said control means comprising a spring mounted to exert a force in the direction of the blade, and a rigid member connected at one end to said spring and at the other end to said blade adjacent the periphery of the latter, said member being radially disposed relative to said blade when the latter is in equilibrium position and being rendered eccentric relative to said blade by the pivotal displacement of the latter whereby said spring applies a torque to said blade tending to increase any pivotal displacement thereof from equilibrium position, and means adapted to convert the lateral displacement of the blades into a turning torque applied to said blades, the latter torque tending to further increase the pivotal displacement of said blades from said equilibrium position.

4. In a variable pitch propeller comprising one or more blades supported so as to be pivoted and laterally displaced from a predetermined initial equilibrium position relative to the hub thereof by the forces set up when said propeller is rotated in a fluid medium, resilient supporting members for said blades, said members having axes laterally displaced from and obliquely disposed to the axis of rotation of said propeller, said supporting members opposing the angular and lateral displacements of said blades relative to the hub, means adapted to convert the lateral displacement of said blades into a turning torque tending to further angularly displace said blades from said equilibrium position, and control means for each of said blades, each of said control means comprising resilient means mounted on said hub to exert a force in the direction of the blade, and a rigid member connected at one end to said resilient means and at the other end to said blade adjacent the periphery of the latter, said member being radially disposed relative to said blade when the latter is in equilibrium position and assuming an eccentric position relative thereto when said blade is pivotally displaced whereby upon pivotal displacement said resilient means applies a torque to said blade tending to increase said pivotal displacement.

5. In apparatus of the class described, a plurality of pivot rods, a blade secured to each rod, the axis of each of said rods being inclined relative to the axis of the blade secured thereto, a driving shaft, a hub operatively connected to said shaft, means upon said hub for mounting each of said rods, the axes of said shaft and rods being non-intersecting, means responsive to lateral displacement of each blade upon the hub for assisting a pivotal movement of the blade after said movement has begun from a predetermined position of the blades, and control means for each of said blades, each of said control means comprising resilient means mounted on said hub to exert a force in the direction of the blade, and a rigid member connected at one end to said resilient means and at the other end to said blade adjacent the periphery of the latter, said member being radially disposed relative to said blade when the latter is in equilibrium position and assuming an eccentric position relative thereto when said blade is pivotally displaced whereby upon pivotal displacement said resilient means applies a torque to said blade tending to increase said pivotal displacement.

DIMITRI SENSAUD DE LAVAUD.
